UNITED STATES PATENT OFFICE.

HARRY W. BROADY, OF BAYSIDE, NEW YORK, ASSIGNOR TO WELIN MARINE EQUIPMENT CO., A CORPORATION OF NEW YORK.

DEVICE FOR SECURING AND RELEASING LIFE-BOATS.

1,118,527.

Specification of Letters Patent.

Patented Nov. 24, 1914.

Application filed January 8, 1913. Serial No. 740,807.

To all whom it may concern:

Be it known that I, HARRY W. BROADY, a citizen of the United States, and a resident of Bayside, borough of Queens, county of 5 Queens, and State of New York, have invented certain new and useful Improvements in Devices for Securing and Releasing Life-Boats, of which the following is a specification.

- 10 This invention relates to improvements in devices for securing and releasing life-boats and particularly to that type of device wherein a lifeboat mounted on a suitable pivoted support secured to the deck of 15 a vessel is adapted to be tilted about its longitudinal axis by rocking the support on its pivot.
- 20 The object of the present invention is to improve this type of device whereby the launching of a lifeboat or a plurality of nested lifeboats will be greatly facilitated, and with this end in view, a feature of the present invention consists in the provision of a support for one or more lifeboats pivoted on 25 the deck of a vessel, means for securing the lifeboat to such support and means for tilting the support, comprising a link pivoted intermediate its ends and having one end connected to said support and an actuating 30 lever for rocking said link fulcrumed on a suitably supported movable pivot.

Another feature of my invention consists in the provision with such a suitable support of a plurality of nested lifeboats mounted 35 thereon, flexible connections for securing the lower boat to such pivoted support, flexible connections for securing an upper boat in place on the lower boat, means for rocking the support to tilt both lifeboats and means 40 for releasing the flexible connections of the upper of said nested lifeboats simultaneously with the tilting of the support to permit an immediate suspension of said upper boat by suitable davits.

45 The preferred embodiment of my invention comprises a rigid supporting cradle for one side of each end of a lifeboat, each cradle preferably composed of two members secured to the deck of the vessel and having 50 their inboard ends terminating in cradling blocks or uprights having curves conforming to the shell of the boat, the outboard ends of such members, or that portion extending outboard beyond the longitudinal axis of the boat, preferably being cut down

or inclined downwardly toward the edge or side of the ship, and these two rigid, stationary supporting members not only form a cradle for the inboard side of the boat but also form raised bearings for a short shaft 60 extending parallel to the keel or longitudinal axis of the boat, on which shaft is pivoted a rocking beam which is positioned between such stationary members; is normally retained in horizontal position and contacts 65 with the bottom of the lifeboat so supported at the inboard side by the stationary members; gripes for securing the lower boat in position on said beam, such gripes preferably extending from a ring at the outboard 70 end to a ring at the inboard end thereof; independent gripes for securing the upper boat in position on the lower boat, preferably connected at the outboard end to a ring in the deck and at the inboard end to a hook 75 disengaged by the actuation or upward movement of the rocking beam; and means for rocking said rocking beam to tilt the boats and locking the same in its extreme positions, comprising an angular rocking 80 link pivoted to swing on a suitable support, such as a bracket secured to the side edge of one of the two upright portions or cradling blocks of the supporting cradle, one arm of said link being connected by means of a universal link pivoted to the rocking beam and the other arm preferably being connected by means of a connecting rod to an angular link similarly pivoted and similarly connected to a twin rocking beam at 85 the other end of the boat; and means for swinging said rocking link on its pivot to rock the twin beams to tilt the boats, said link rocking means comprising a swinging or traveling connection with a movable pivot 90 preferably guided to travel or reciprocate in a vertical plane substantially in alignment with said link pivot by means of a slot formed in the aforesaid bracket, the movable pivot being provided with a roller extending into a transverse arc-shaped slot in the link; an actuating lever having one end pivotally engaging the link and an intermediate pivotal connection with the guided movable or reciprocating pivot.

100 In the accompanying drawings, in which similar reference characters designate corresponding parts throughout the several views, Figure 1 is a side view of two boats supported and secured by my improved de- 105 110

- 2
- vice; Fig. 2 is an end elevation of the device illustrated in Fig. 1; Fig. 3 is an enlarged end elevation of a device embodying my invention, the boats being removed; Fig. 4 is a plan view of the device shown in Fig. 3; Fig. 5 is an enlarged side elevation of the inboard side of said device; Fig. 6 is an end elevation of a device embodying my invention in elevated or tilted position, the upper boat and portion of the lower boat being broken away; and Fig. 7 is an enlarged side elevation similar to Fig. 5, the mechanism being shown in the opposite extreme position.
- 15 Referring now to these drawings, 1 designates the deck of the vessel to which is rigidly secured twin supporting cradles 2 for the inboard side of a lifeboat. The cradles 2 are preferably bolted to the deck 20 so that a boat supported thereon will assume a horizontal position and when the deck is rounded, as shown, I provide foundation blocks or sleepers 3 to obtain the desired horizontal position. Each of the twin 25 cradles, as shown, comprise two rigid and stationary cradle beams 2' and 2" respectively, and the inboard side of each cradle beam has an upright portion 8 having a curve 9 conforming to the bottom of the life- 30 boat. As shown, a flat-bottomed boat 4 rests at its inboard side in the cradles, and another flat-bottomed boat 5 is nested or supported thereon and is suspended from twin davits 6-6 by means of blocks and 35 falls 7-7. Obviously if the boat 4 were a round bottom boat the curve 9 would be changed to correspond thereto. As illustrated, the outboard side of such stationary cradle beams are cut down or inclined to 40 ward the deck so as to leave such outboard end entirely free and unobstructed when the boats are tilted as hereinafter described, and this outboard end may be entirely cut away without materially affecting my in- 45 vention.
- A tilting beam 10 is pivoted intermediate its ends on an axle or shaft 11 bearing in brackets 12 and 13 secured to the stationary cradle beams 2' 2" respectively, and said beam is normally retained in horizontal position and contacts at both sides of its pivot with the bottom of the boat 4 which is securely retained in position thereon by means of a gripe chain 15 or other suitable 50 flexible connection which extends completely around the boat from a ring 13 at the outboard side of the tilting beam 10 to a ring 14 at its inboard side, the inboard side of the gripe 15 being provided with a pelican hook 16 to permit the ready connection with the ring 14.
- The upper of the two nested boats 5 is, as illustrated, retained in place on the lower boat by means of a gripe chain 17 connected 55 at the outboard side to a ring 18 in the deck and at its inboard side to a hook 19 which will be moved to disengage therefrom simultaneously with the tilting of the boats as will now be described.
- The boats being secured in position as 70 above described, if the beam 10 is rocked on its axle or shaft 11, both boats will obviously be tilted from their normal horizontal position to a position in which the inboard side will be considerably raised 75 above such normal horizontal position and the outboard side lowered considerably below such normal horizontal position, the boats' rocking or tilting together about a common horizontal axis, and it will be apparent that the upper boat which, as aforesaid, is suspended from the davits will in launching readily clear the outboard gunwale of the lower boat and may be launched from such tilted position with much greater 80 facility and rapidity than would be possible if it remained in horizontal position. When it is desired to launch the lower boat of two or more nested boats or a single boat, the 85 tilting thereof will under some conditions 90 be very effective for permitting and assisting in its rapid launching, as for example, when a ship or vessel carrying the lifeboat is listed to the side opposite to that on which the boat is mounted, the tilting thereof by 95 my device will compensate for the list of the vessel and permit the launching of a boat which it would otherwise be impossible to launch. In nested lifeboats, however, such 100 tilting is essential to a rapid landing when the ship or vessel is on an even keel, it being impractical to chock lifeboats one on top of the other in the ordinary way in which a boat is chocked on the deck, and it is therefore necessary either to tilt the 105 nested boats toward the outboard side of the vessel so that in launching the bottom of the upper boat will clear the gunwales of the lower, or the upper boat must be raised bodily considerably above the lower 110 boat.
- As will be understood from the foregoing, I preferably provide twin retaining and tilting devices, one for each end of the lifeboat or lifeboats, but under certain conditions, 115 one set of such devices at the center of the boat will be sufficient.
- I will now describe my preferred means for rocking the tilting beam or beams. It is desirable that this shall be accomplished 120 by manual power and it is of vital importance that no time be lost. I have, therefore, devised lever and link mechanism for this purpose by means of which one man with very little effort will be enabled instantaneously to tilt two or more boats. In the preferred form of this lever and link mechanism illustrated, an angular rocking link 125 20 is pivoted at 21 to a bracket 22 secured to the inboard side of the upright portion 8 130

of one of the cradle beams 2'', has an arm 26 extending laterally therefrom and pivotally connected by means of a universal link 27 to the tilting beam 10; another arm 29 extending at an angle from the connecting arm and pivotally connected by connecting rod 30 to another angular link 31, which is pivoted at 32 to an upright portion 8 of the cradling device at the opposite end and 10 has a similar pivotal connection with the tilting beam at said end. With suitable power-applying devices the links at both ends may be rocked simultaneously by one man to lift the beams at the inboard ends 15 and I have provided an extremely simple power-applying device which not only permits its lifting and lowering the tilting beams at both ends simultaneously but automatically locks such beams in extreme positions. Thus, I provide a connection between 20 the arm 29 of the angular link 20 and a movable pivot 24, which is in the form of a roller and travels or reciprocates in a vertically-disposed slot 25 in the fixed bracket 22, by 25 means of an actuating lever 28 which is pivoted at one end to the arm 29 of said link and is fulcrumed intermediate its ends on said movable pivot 24, said connection between the slot 25 and lever preferably being 30 made by extending said pivot 24 laterally through an arc-shaped slot 23 in the arm 29 of said link 20. In the normal position of the device, when used in connection with two boats, the gripe chains for securing the 35 upper boat will be secured at their inboard ends, as aforesaid, to the hooks 19 of the links 20 and 31 and the rocking of the links will simultaneously lift the tilting beams and release the gripes at the inboard side. 40 It will be noted that by the use of the power-applying device just described, the lever 28 will be most effective when most needed and that the mechanism will be locked in its extreme positions; that at the 45 start of the movement of the lever, the movable pivot 24 will move upwardly in the slot 25 and the link, which is movable on its pivot 21, will begin to swing, the arm 29 to which power is applied moving toward 50 the load and the line of pull at the beginning of movement being from the end of the lever to the movable fulcrum and upwardly to the pivot. Obviously at the start of the movement of the lever, at which point the 55 greatest amount of power is required, this arrangement will cause the pull to be of infinite strength, and, as the movable pivot moves further upwardly in its slot and the end of the arm 29 of the link moves around 60 such movable pivot, the line of pull will gradually approach a vertical straight line and only a small amount of power will be necessary until it passes again to a right angular pull on the other side of the vertical 65 plane in which the pivot of the link lies,

when by further rotation of the lever, the device may be readily locked in the opposite extreme position. The reverse motion will, of course, bring the parts back to normal position, and the last link of gripe chain for 70 the upper boat will be placed beneath the hook before the link reaches extreme position.

Having described my invention I claim:—

1. The combination with a support for a 75 lifeboat pivoted on the deck of a vessel, means for securing the lifeboat to such support, a link pivoted intermediate its ends and having one end connected to said pivotal support and means for rocking said 80 link, comprising an actuating lever pivoted to said link and fulcrumed on a suitably supported movable pivot.

2. The combination with a stationary cradle for the inboard side of a lifeboat, of a 85 supplementary support pivoted on the deck of a vessel and contacting with both inboard and outboard sides of the bottom of the lifeboat, means for rocking such support to tilt the lifeboat and means for locking such pivotal support to the stationary cradle to retain the same in extreme positions.

3. The combination with a suitable stationary support for the inboard side of a 95 lifeboat, of another support pivoted intermediate its ends and contacting with the bottom of the lifeboat, an angular link pivoted to said stationary support having one arm pivotally connected to said pivoted support, means for locking such link to said 100 stationary support to retain the pivoted support in horizontal and inclined positions respectively.

4. The combination with a suitable stationary support for the inboard side of a 105 lifeboat, of another support pivoted intermediate its ends and contacting with the bottom of the lifeboat, an angular link pivoted to said stationary support having one arm pivotally connected to said pivoted support, a movable pivot supported in a slot in the said stationary support, a connection between such movable pivot and the opposite arm of said link and means for rocking said link to opposite sides of said movable pivot. 110

5. The combination with a suitable stationary support for the inboard side of a lifeboat, of another support pivoted intermediate its ends and contacting with the bottom of the lifeboat, an angular link pivoted to said stationary support having one arm pivotally connected to said pivoted support, a movable pivot supported in a slot in the said stationary support, an actuating lever fulcrumed on said movable pivot and 115 pivoted to said link for swinging the same to opposite sides of said movable pivot and locking the pivotal support in horizontal and inclined positions respectively.

6. The combination with a plurality of 120

44
nested lifeboats, of a suitable support pivoted on the deck of a vessel, flexible connections for securing the lower boat to such pivoted support, flexible connections for securing an upper boat in place on the lower boat, davits and means for suspending the upper boat therefrom, means for retaining such support in horizontal position, means for rocking the same to tilt both lifeboats and means for releasing the flexible connections of the upper boat simultaneously with the tilting of said support.

7. The combination with a plurality of nested lifeboats, of a suitable support pivoted on the deck of a vessel, flexible connections for securing the lower boat to such pivoted support, flexible connections for securing an upper boat in place on the lower boat, davits and means for suspending the upper boat therefrom, means for retaining such support in horizontal position, means for rocking the same to tilt both lifeboats, comprising an angular link suitably pivoted intermediate its ends and having an arm pivotally connected to said pivoted support.

8. The combination with twin pivotal supports for opposite ends of a lifeboat, an-

gular links for each of such twin pivotal supports, each pivoted intermediate its end and having an arm pivotally connected to one of said twin pivotal supports, means for connecting the other arm of such angular links and means for rocking one of such links to rock the twin supports on their respective pivots and for locking the same in horizontal and inclined positions respectively.

9. The combination with twin pivotal supports for opposite ends of a lifeboat, angular links for each of such twin pivotal supports, each pivoted intermediate its end and having an arm pivotally connected to one of said twin pivotal supports, means for connecting the other arm of such angular links and means for rocking one of such links to rock the twin supports on their respective pivots.

In witness whereof, I have signed my name to the foregoing specification in the presence of two subscribing witnesses.

HARRY W. BROADY.
